UNITED STATES PATENT OFFICE.

ROWLAND J. DARNELL, OF MEMPHIS, TENNESSEE.

MACHINE FOR MAKING WIRE BALE-TIE LOOPS.

SPECIFICATION forming part of Letters Patent No. 677,956, dated July 9, 1901.

Application filed February 4, 1901. Serial No. 45,955. (No model.)

To all whom it may concern:

Be it known that I, ROWLAND J. DARNELL, a citizen of the United States, residing at Memphis, Shelby county, State of Tennessee, have 5 invented certain new and useful Improvements in Machines for Making Wire Bale-Tie Loops, of which the following is a specification.

My invention relates to machines for forming wire bale-tie loops, and more especially to machines which form loops by bending and wrapping one end of the wire around the body of same without twisting them together and thereby weakening them. Such a tie is shown 15 in process of being formed in the drawings hereto appended.

The object of my invention is to provide a simple and efficient machine for making wire bale-tie loops.

20 It is my especial object, further, to provide a machine to make the form of bale-tie loop hereinbefore referred to.

Heretofore in machines of this class it has been customary to form a loop approximating 25 more or less to a circular form and to then catch this loop and the two parts of wire folded together and to complete the loop by twisting them together.

My machine has for its object to form the 30 loop or eye carefully and having so formed it to wrap the free end of the wire around the body of same, and thereby finish the loop without in any way damaging the wires by an injurious twisting process.

35 In the drawings, Figure 1 is a perspective view of the machine from the rear and side. Fig. 2 is a section on the line II II of Figs. 1 and 3. Fig. 3 is a partial sectional elevation on the line III III of Fig. 2. Fig. 4 is a sectional elevation, partially in detail, to show the wrapping-spindle in position to begin the wrapping of the free end of the wire around the body of same to complete the loop. Fig. 5 is a fragmental elevation to show action of 45 a detail.

Referring now to the drawings, in which like parts are indicated by like numerals in all the views, 1 is the base or foundation plate. A tail-stock 2 is mounted on said base-plate 50 and carries a mandrel 3, axially fixed but movable longitudinally, so that it may be withdrawn to release the wire loop or eye 4,

formed around it; in the manner hereinafter to be more fully set forth. 5 is a handle on this mandrel 3, which is grasped to withdraw 55 same. 6 is a collar fastened on said mandrel and acted on by a spring 7 to hold the mandrel in place and to return it to place when it has been withdrawn to drop the finished loop 4. The tail-stock 2 is hollowed out to 60 carry the spring 7, which is held in place by a collar 8, which I have shown screwed in.

Opposite the mandrel 3 and axially in line therewith is a rotatable eye-forming spindle 9, which is used to form the loop 4. This 65 eye-forming spindle is carried by bearings 10, which are fastened to the base 1, as the tail-stock is. This spindle 10 is hollow at 11 to receive the mandrel 3 and is slidably mounted in the said bearings 10 and the pulley 12, 70 which is keyed on it with a feather-key sliding in a keyway in the spindle.

13 is a loosely-mounted hand-grip for forcing the spindle inward into contact with the wire 14 (shown dotted in Fig. 2) to form the 75 loop 4.

15 is a spring for withdrawing the spindle 9 when the hand-grip 13 is released after the loop 4 has been completed.

16 is a cord or belt fastened to the pulley 80 12 by a rivet 17 and wrapped twice around said pulley, so that a pull in one direction will rotate this pulley two turns and a pull in the opposite direction will rotate it back to its original position. One end of this belt 85 or cord passes over the pulley 18, which is supported by a bracket 19 and descending thence through a hole 20 in the base-plate 1 is fastened to a weight (not shown) to retract the cord, and thereby rotate the pulley 12 and 90 spindle 9, on which it is fastened, to their original position when the loop or eye 4 has been finished. The other end of the cord 16 (designated beneath the base as 21) is fastened to a treadle or like means, (not shown,) 95 by which it may be depressed sufficiently to rotate pulley 12 and spindle 9 one, two, or more turns, as the case may be.

22 is a notch or slot formed in the end of the spindle 9 to catch the wire 14 and make 100 the loop 4. To form this loop the cord 16 is so arranged that the spindle receives nearly two complete revolutions, which revolutions are such as to take the wire in the horizontal

dotted position 14, Fig. 4, and after carrying it once completely around the mandrel 3 to leave it in the position 33, (shown in Fig. 4,) inclined slightly from the vertical and in such 5 position that it is ready to be caught by the wrapping-spindle and the tie end completed.

23 is a wrapping-spindle which completes the operation of forming the tie. This spindle is located in the same horizontal plane as 10 the mandrel and the eye-forming spindle and at right angles to them. It is longitudinally fixed in bearings 24, which are carried by a bracket 25, adapted to slide in a dovetail guide 26 on the base 1.

15 27 is a handle pivoted to a standard 28 on the base and fastened by a pin and cotter 29 to the sliding bracket 25. The bearing in the handle 27 at the standard 28 is slotted to allow sufficient play for the circular sweep of 20 the handle.

The wrapping-spindle 23 is constantly rotated by a belt 30, passing around a pulley 31 on said spindle, and has a notch or slot 32, similar to that on the eye-forming spindle, to 25 wrap the free end 33 of the wire around the body of the wire 34 after the loop or eye 4 has been formed. This spindle is made hollow, and the wire 34 for the ties enters centrally through it. The tail-stock is cut away at 35 30 to permit this spindle to come sufficiently close to catch the wire and begin wrapping the free end 33 of same.

36 is a clamp to hold the wire during the entire process of forming the loop or eye 4 and 35 of wrapping the free end 33. This clamp is normally held away from the lower block 37 of the clamp by a spring 38. (Shown in Fig. 2.) This clamp is held in place and guided by ears 39, which extend upward from the 40 block 37 on each side and serve also to carry a bolt 40, on which an eccentric clamping-handle 41 is pivoted. Holes 42 permit the passage of the wire through the ears 39. The block 37 is bolted to the base 1.

45 In Figs. 2 and 3 I show the free end 33 of the wires extending directly upward, the wrapping not having been completed, as shown in these figures, and in Fig. 4 I show the wrapping-spindle 23 in position to begin.

50 43 (especially shown in Fig. 5) is a guide for the free end 33 of the wire during the process of forming the loop 4. In making this loop I find that the free end 33 of the wire sometimes has a tendency to go behind the body- 55 wire 34, in which case the operation of making the loop is effectually blocked. To prevent such a contingency, I make use of the guide 43. This guide is pivoted at 44 and is thrown forward by a cam 45, carried by the 60 sliding bracket 25, when the bracket has been drawn back after completing the wrapping of the free end 33, and when so thrown forward the upper end of the guide passes under the wire 34 and beyond same, so that the free 65 end 33 of the wire strikes the forward edge of the guide and is directed past the body-wire 34. When the bracket 25 is moved for-

ward, however, the cam 45 depresses the L-shaped arm of the guide 43 and withdraws same into the dotted position shown in Fig. 70 5, out of the way of the wrapping-spindle 23.

Means for cutting the wire to length and for feeding and measuring same are not shown herein.

In operation the wire is moved forward until the free end projects the proper distance beyond the mandrel 3 in the dotted position 75 14. The clamp 36 is set to hold the wire, and the eye-forming spindle is pushed forward by means of the hand-wheel 13 until the notch 80 or slot 22 engages the wire 33. The belt 21 is then pulled downward and the spindle 9 thereby rotated until the free end 33 comes into the position shown in Fig. 4, the guide 43 forcing the end 33 to pass the body 34 of 85 the wire. The belt 21 is then released, and the belt 16 rotates the spindle 9 back to its former position. The wrapping-spindle 23 is next moved forward by means of the handle 27 until the notch 32 engages the free end 33 90 of the wire, as shown in Fig. 4. As soon as this notch catches the end 33 the handle 27 is released. The spindle 23, rotating rapidly, wraps or winds the free end 33 of the wire 95 around the body-wire 34 and as the spiral is thus formed is forced back by it until the end is reached. The mandrel 3 is next pulled back and the finished loop dropped off. The desired length of wire is measured and the tie cut off, leaving the free end ready to be 100 formed into another loop.

Various changes in the details of my invention may be made without departing from the same. The slot 22 in the spindle 9 and the slot 32 in the wrapping-spindle may be modified in form, and other like detail changes 105 not affecting the merits of the invention may be made.

Having now fully described my invention, what I claim, and desire to secure by Letters 110 Patent of the United States, is—

1. In a machine for forming wire bale-tie loops, the combination with an axially-fixed mandrel as an eye or loop center, a rotatable spindle mounted axially in line therewith, means of moving said spindle a predetermined amount, means on the end thereof to engage a wire to wrap same around said mandrel to form an eye, and means of guiding the end of said wire while the loop is being 120 formed, of means of wrapping the wire upon itself after the said eye has been formed, substantially as shown and described.

2. In a machine for forming wire bale-tie loops, the combination with an axially-fixed 125 mandrel as an eye or loop center, a rotatable spindle mounted axially in line therewith, means of moving said spindle axially, means of rotating said spindle a predetermined amount, and means on the end thereof to engage a wire to wrap same around said mandrel to form an eye, of a continuously-rotating 130 spindle to wrap the wire upon itself after the said eye has been formed and means of

retracting the wrapping-spindle automatically when the wrapping is complete, substantially as shown and described.

3. In a machine for forming wire bale-tie loops, the combination with an axially-fixed mandrel as an eye or loop center, a rotatable spindle mounted axially in line therewith, means of moving said spindle axially, means of rotating said spindle a predetermined amount, and means on the end thereof to engage a wire to wrap same around said mandrel to form an eye, of means of guiding the end of said wire while the loop is being formed, and means of retracting said mandrel to release said loop when it is completed, substantially as shown and described.

4. In a machine for forming wire bale-tie loops, the combination with an axially-fixed mandrel as an eye or loop center, a rotatable spindle mounted axially in line therewith, means of moving said spindle a predetermined amount, means on the end thereof to engage a wire to wrap same around said mandrel to form an eye, a guide pivoted to the mandrel-frame, and means of throwing same forward to guide the end of said wire while the loop is being formed, substantially as shown and described.

5. In a machine for forming wire bale-tie loops, the combination with an axially-fixed mandrel as an eye or loop center, a rotatable spindle mounted axially in line therewith, means of moving said spindle a predetermined amount, means on the end thereof to engage a wire to wrap same around said mandrel to form an eye, a pivoted guide, a cam and means of moving same forward and retracting same, to throw the said guide out of and into action to guide the end of said wire while the loop is being formed, substantially as shown and described.

6. In a machine for forming wire bale-tie loops, the combination with means of forming an eye near one end of a wire, of a continuously-rotating wrapping-spindle concentric with said wire to catch the free end and wrap it around the body of said wire, to complete the loop, substantially as shown and described.

50 7. In a machine for forming wire bale-tie loops, the combination with means of forming an eye, near one end of a wire, of a continuously-rotating spindle, a catch on said spindle to catch the free end and wrap it around the body of said wire, to complete the loop, substantially as shown and described.

8. In a machine for forming wire bale-tie loops, the combination with means of forming an eye near one end of a wire, of a continuously-rotating wrapping-spindle concentric with said wire, a catch on said spindle to catch the free end and wrap it around the body of said wire, to complete the loop, and means of releasing said loop when completed, substantially as shown and described.

65 9. In a machine for forming wire bale-tie

loops, the combination with an axially-fixed mandrel as an eye or loop center, a rotatable spindle mounted axially in line therewith, means of moving said spindle axially, means of rotating said spindle a predetermined amount, means on the end thereof to engage a wire to wrap same around said mandrel to form an eye, and means of guiding the end of said wire while the loop is being formed, of a continuously-rotating wrapping-spindle, means of moving said spindle forward to engage the wire and complete the tie, and means of automatically withdrawing said wrapping-spindle when the tie is complete, and means of retracting said mandrel to release said loop, substantially as shown and described.

10. In a machine for forming wire bale-tie loops, the combination with means of forming an eye near one end of a wire, of a rotating wrapping-spindle concentric with said wire, means of moving said spindle longitudinally, a catch on said spindle to catch the free end of said wire and wrap it around the body of same to complete the loop, means of causing the wrapping-spindle to follow the wrapped wire and of automatically releasing itself at the completion of said wrap, and means of releasing said loop when completed, substantially as shown and described.

11. In a machine for forming wire bale-tie loops, the combination with a mandrel as an eye-center, and a spindle, with a notch in the end of same to engage a wire and form same into a loop around said mandrel, and means of rotating said mandrel a predetermined amount, of a continuously-rotating spindle to wrap the end of the wire around the body of same and complete the loop, substantially as shown and described.

12. In a machine for forming wire bale-tie loops, the combination with a mandrel as an eye-center, and a spindle, for forming a wire into an eye around said mandrel, of a continuously-rotating spindle, to wrap the end of the wire around the body of same and complete the loop, means of clamping and holding the wire during the entire operation, and means of releasing the loop from said mandrel, and said clamp, when the operation has been completed, substantially as shown and described.

13. The combination with a mandrel and a looping-spindle axially in line therewith, of a continuously-rotating wrapping-spindle at right angles thereto axially movable, and means of moving said spindle axially to engage the free end of the wire, substantially as shown and described.

14. The combination with a mandrel and a looping-spindle axially in line therewith, of a hollow wrapping-spindle at right angles thereto to permit a wire being fed through said hollow spindle, substantially as shown and described.

15. The combination with a mandrel and a looping-spindle axially in line therewith, of

a hollow wrapping-spindle at right angles thereto, and a wire-clamp, substantially as shown and described.

16. The combination with a mandrel and a looping-spindle axially in line therewith, of a hollow wrapping-spindle at right angles thereto, and a wire-clamp located in line with the center of said hollow spindle, substantially as shown and described.

17. The combination with a mandrel and means of retracting and replacing same, a looping-spindle axially in line therewith, means of moving said looping-spindle forward, and rotating same a predetermined amount, and of rerotating and retracting same, of a rotating hollow wrapping-spindle concentric with the line of wire-supply, all substantially as and for the purposes set forth.

18. The combination with a mandrel and means of retracting and replacing same, a looping-spindle axially in line therewith, means of moving said looping-spindle forward, means of rotating same a predetermined amount and of rerotating and retracting same, of a rotating hollow wrapping-spindle concentric with the line of wire-supply and a wire-clamp, all substantially as and for the purposes set forth.

19. The combination with a mandrel and means of retracting and replacing same, a looping-spindle axially in line therewith, means of moving said looping-spindle forward, means of rotating same a predetermined amount, and of rerotating and retracting

same, and a wire-guide to direct the wire during the looping operation, of a rotating hollow wrapping-spindle concentric with the line of wire-supply, all substantially as and for the purposes set forth. 35

20. The combination with a mandrel and means of retracting and replacing same, a looping-spindle axially in line therewith, means of moving said looping-spindle forward, of rotating same a predetermined amount and of rerotating and retracting 40 same, of a rotating hollow wrapping-spindle concentric with the line of wire-supply, means of bringing said wrapping-spindle forward, and a wire-clamp, all substantially as and for the purposes set forth. 50

21. The combination with a mandrel and means of retracting and replacing same, a looping-spindle axially in line therewith, means of moving said looping-spindle forward, of rotating same a predetermined 45 amount, and of rerotating and retracting same, and means of moving said guide forward and backward automatically, of a rotating hollow wrapping-spindle concentric with the line of wire-supply, all substantially as and for 55 the purposes set forth.

In testimony whereof I have signed my name to this specification in the presence of two subscribing witnesses.
